UNITED STATES PATENT OFFICE.

FREDERIC L. BAXTER, OF GRAND RAPIDS, MICHIGAN.

SAFETY APPLIANCE FOR CENTRIFUGAL WRINGERS.

981,833.

Specification of Letters Patent. Patented Jan. 17, 1911.

Application filed March 21, 1910. Serial No. 550,625.

To all whom it may concern:

Be it known that I, FREDERIC L. BAXTER, a citizen of the United States of America, residing at Grand Rapids, in the county of Kent and State of Michigan, have invented 5 certain new and useful Improvements in Safety Appliances for Centrifugal Wringers; and I do hereby declare the following to be a full, clear, and exact description of 10 the invention, such as will enable others skilled in the art to which it appertains to make and use the same.

My invention relates to improvements in safety appliances for centrifugal wringers, 15 and its object is to provide an improved hinged cover for such wringers; to provide improved means for preventing the opening of the cover when the machine is running; to simplify the device, and to provide the 20 same with various new and useful features hereinafter more fully described and particularly pointed out in the claims.

My invention consists essentially in the improved construction of the cover, and in 25 the combination and arrangement of the cover and belt shifter, whereby the cover will not stay opened until the belt is shifted to the loose pulley and the belt may be so shifted without opening the cover, as will 30 more fully appear by reference to the accompanying drawings, in which:

Figure 1 is a side elevation of a centrifugal wringer with my improvement applied thereto, shown with the cover closed, 35 and the belt shifted to the tight pulley; Fig. 2 a portion of the same showing the belt shifted to the loose pulley and the cover opened; Fig. 3 a plan view of my improved cover; and, Fig. 4 an enlarged detail of the 40 same shown in vertical section.

Like numbers refer to like parts in all of the figures.

1 represents the usual form of centrifugal wringer; 2 the driving belt for the same; 3 the loose pulley; 4 the tight pulley; 5 the arms of the belt shifter; 6 the handle of the belt shifter; and 7 the longitudinally slid able rod of the same. These parts are so arranged that the handle 6, when the belt is 50 shifted to the tight pulley, will project over the rear of the cover 8 to such an extent that the said cover will engage the same before it is turned to a vertical position, and thus the cover will fall back to closed position by 55 gravity if opened. The length of the rod 7 is such that when the belt is shifted to the

loose pulley 3, the handle 6 will be moved back away from over the machine sufficient distance to permit the cover to be opened slightly beyond the vertical position and rest 60 against the handle in this open position. The handle thus affords a safety stop to prevent the cover from remaining open when the machine is running, and also a substantial support for the cover when the machine 65 is not running and the cover is opened.

The structure is also much simplified for 70 that no additional parts are required to be attached to either the cover or the belt shifter.

My improved cover as represented in Figs. 3 and 4, comprises a ring 9 preferably made of round rod or wire and provided with a straight or chordal portion 10 of the full width of the hinge part. A woven wire 75 structure convex in form as at 8 is secured to this ring 9 by bending the ends of the wires of said structure around the ring and forms a very satisfactory and substantial cover. The hinge for the cover also comprises a 80 plate 11 having a series of arms 12 spaced apart and turned around the chordal or straight portion 10 of the ring 9, thus forming a very substantial and simple hinge for the same.

The construction of the cover herein shown is not herein claimed but is reserved for a separate application in accordance with a requirement of division.

What I claim is:

1. A safety appliance for centrifugal wringers, comprising a hinged cover adapted to project within the path of the belt shifter when said cover is opened and the belt shifter movable independently of the cover projecting above the cover when shifted to running position to engage the cover and prevent the same from remaining open and supporting the cover in open position when shifted to non-running position.

2. A safety appliance for centrifugal wringers, comprising a hinged cover a belt shifter having a slid able rod movable independently of the cover, directly behind the cover and carrying a handle adapted to project over the cover and engage the same before the cover is raised to a vertical position, and adapted when shifted to engage and support the cover in open position when the same is turned beyond the vertical position.

3. A safety appliance for centrifugal wringers, comprising a hinged cover and a

- belt shifter movable independently of the cover adapted when in running position to project over the cover and engage the same before said cover is raised to a vertical position, and when shifted to stop the machine permits the cover to pass the vertical position and also engages and supports the same in open position.
4. A safety appliance for centrifugal wringers, comprising a tight and loose pulley, a driving belt, a belt shifter having a slideable rod, a hinged cover beneath the rod

and engaged thereby to prevent said cover from remaining open when the shifter is moved to shift the belt to the tight pulley, 15 and when shifted to move the belt to the loose pulley and the cover opened up, engages and supports the cover.

In testimony whereof I affix my signature in presence of two witnesses.

FREDERIC L. BAXTER.
